UNITED STATES PATENT OFFICE.

ERNEST L. GENTIS, OF NEWPORT NEWS, VIRGINIA.

TROLLEY-FORK.

SPECIFICATION forming part of Letters Patent No. 703,782, dated July 1, 1902.

Application filed February 21, 1902. Serial No. 95,093. (No model.)

To all whom it may concern:

Be it known that I, ERNEST L. GENTIS, a citizen of the United States, residing at Newport News, county of Warwick, and State of Virginia, have invented a certain new and useful improvement in Trolley-Forks, of which the following is a specification.

My invention relates to a new and useful improvement in trolley-forks, and has for its object to provide a trolley-fork by which the trolley-wheel will be allowed a certain amount of movement separate from its rotary motion and at the same time not altering its contact with the electrical conductors, so as not to cause any undue loss in the transmission of the electric current.

With these ends in view this invention consists in the details of construction and combination of elements hereinafter set forth and then specifically designated by the claims.

In order that those skilled in the art to which this invention appertains may understand how to make and use the same, the construction and operation will now be described in detail, referring to the accompanying drawings, forming a part of this specification, in which—

Figure 1 is a side elevation of the trolley-fork, the protecting-cap upon that side being removed to better illustrate the invention; Fig. 2, a longitudinal section of the fork; Fig. 3, a section on the line 3 3 of Fig. 1.

A represents the two members of the prongs of the trolley-fork, which are joined together and secured in any suitable manner to the trolley-pole B. The outer ends of each of the forks or members are circular in form and have formed through the same circular openings, the edges of which openings are journaled, as illustrated at C.

D represents guide-plates, the sides of which are parallel with one another; but the ends are rounded to correspond with the opening formed through the ends of the forks. These rounded ends of the plates D are shouldered, so as to lie within the channel C, formed in the periphery of the circular opening through the fork. The channels C do not extend entirely around the openings, but terminate so as to leave two portions E solid or flush with the outside of the fork, and these solid portions will come opposite one another. Out-

side of the plates D are secured the caps F, one upon each side, and these caps are secured to the fork by means of screws G, which pass through holes formed in the caps and are threaded into the fork through the solid portions E, as shown in Figs. 1 and 3. The rims of these caps will be broad enough to overlap the ends of the plates D, such ends being flush with the exterior of the forked members by reason of lying within the channel C, formed in such members. Thus the caps will prevent the members from falling outward, but will allow them to turn within the channel C to a limited extent, they being prevented from turning entirely around by reason of the solid portions E.

H is a slot or guideway formed through each of the guide-plates D, and I represents bearing-blocks, square in cross-section, which are adapted to lie within these slots or guideways, and these bearing-blocks are shouldered upon the inside, so as to prevent them from passing through the guideway.

J is a trolley-wheel which is firmly secured to the axle K, and the ends of this axle or trunnion are shouldered, and the reduced ends beyond the shoulder pass through the bearing-blocks I and have a bearing therein. The shoulders upon the axle come against the inner face of the bearing-blocks, and thus all the parts are in position relative to one another.

The guide-plates D are curved or bulge outward, as shown in Fig. 2, so that the interior of the face of the plates will be concaved. The radius of the curvature of these plates is struck from the center of the axle K. Thus it will be seen that the trolley-wheel J may be twisted or thrown out of a straight line a certain distance, because of the fact that the bearing-blocks I will slide within the slots H in the plates D. This independent movement of the trolley-wheel is for the purpose of allowing said wheel to accommodate itself to the irregularities of the wire, and will also allow the trolley-wheel to shift its position in passing around curves. Therefore much of the undue wear to trolley-wheels will be done away with, as this movement of the trolley-wheel will also prevent the wheel from climbing on the hangers.

It is a well-known fact that much of the

wear and tear upon a trolley-wheel is occasioned by the friction of the wires or hangers against the flanges of the wheel, and if the trolley-wheel can be made to shift its position to accommodate itself to the wire, so that the wire will run in its proper place centrally between the flanges, much of the wear will be done away with.

For the purpose of holding the trolley-wheel straight or in a straight line with the pole normally I provide the two flat springs L, arranged upon each side of the trolley-wheel, and secure each to the inside of one of the prongs of the fork, the free ends of said springs bearing against each side of the trolley-wheel, and thus hold it normally in position. These springs I utilize as conductors for conducting the current from the wheel to the wires carrying the current to the car. Thus as the trolley-wheel shifts its position the springs will follow the same and always maintain a good contact therewith.

The purpose of journaling the plates D within the ends of the prongs of the fork is to allow said plates to always lie parallel with the wire, no matter at what angle the trolley-wheel is standing, and by lying parallel with the wire will always allow the trolley-wheel to twist in a horizontal plane.

A further advantage of my invention other than that set forth in the above description is that all the parts are easily and quickly assembled, so that any new parts may be easily inserted to take the place of any old or worn-out parts, or all the parts may be changed in a very short period of time.

Of course I do not wish to be limited to the exact construction hereshown, as slight modifications could be made without departing from the spirit of my invention.

Having thus fully described my invention, what I claim as new and useful is—

1. In a trolley-fork, circular ends being provided upon the members or prongs of the fork, said ends being provided with circular openings, plates fitted within the openings so as to have a certain amount of rotary movement in the same, each of said plates being curved outward on a radius struck at a point midway between the prongs of the fork, said plates being provided with slots or guideways, bearing-blocks fitted within said slots or guideways, a trolley-wheel, an axle secured to said trolley-wheel, the ends of said axle being journaled within the bearing-blocks, springs so arranged as to normally center the wheel and also act as a conductor for the electric current, and caps secured to the out-

side of the ends of the two members of the fork, substantially as described and for the purpose specified.

2. In a device of the character described, a trolley-fork composed of two prongs or members, each prong or member being provided with a circular opening in their ends, a guide-plate D held within said circular opening but adapted to revolve to a certain extent within the same, said plates being each curved outward upon the radius of a circle struck from a point midway between the forked members, said plates being provided with slots or guideways, bearing-blocks held within said slots or guideways, a trolley-wheel, an axle secured to said trolley-wheel, the ends of said axle being journaled within the bearing-blocks, two flat springs, one arranged upon each side of the trolley-wheel, said springs being secured to the fork and their free ends bearing against the sides of the trolley-wheel to hold the same in alinement, substantially as and for the purpose specified.

3. In a device of the character described, a fork composed of two members, said members being provided with a circular opening through their ends, a channel formed in the ends of the members surrounding the circular opening, guide-plates D having their ends so curved and shouldered as to fit within the channel, said plates being each curved outward upon a radius of a circle struck from a point midway between the forked members, said plates provided with a slot or guideway, bearing-blocks lying within the slots or guideways, said bearing-blocks being shouldered upon the inside, said shoulders coming in contact with the concaved surface of the guide-plates, a trolley-wheel, an axle secured rigidly to said trolley-wheel, shouldered ends formed upon the axle, said ends protruding through openings formed through the bearing-blocks, caps F secured upon the outside of the forked members so as to overlap the ends of the guide-plates and hold them in position against lateral motion, springs so arranged as to normally hold the trolley-wheel in alinement, and also to act as a conductor for conveying the electric current, substantially as described and for the purpose specified.

In testimony whereof I have hereunto affixed my signature in the presence of two subscribing witnesses.

ERNEST L. GENTIS.
